UNITED STATES PATENT OFFICE.

CHARLES H. ALLEN, OF CLAREMONT, NEW HAMPSHIRE.

SOUND-REPRODUCING MECHANISM.

1,276,156.

Specification of Letters Patent. Patented Aug. 20, 1918.

Application filed May 28, 1917. Serial No. 171,561.

To all whom it may concern:

Be it known that I, CHARLES H. ALLEN, a citizen of the United States, residing at Claremont, in the county of Sullivan and State of New Hampshire, have invented 5 certain new and useful Improvements in Sound-Reproducing Mechanism, of which the following is a full, clear, and exact specification.

10 My invention relates to sound reproducing mechanism.

It has for its object to reproduce a record such as those used in phonographs or the like, in an improved manner whereby the 15 full naturalness and full volume of the original sound is reproduced with accuracy. A further object of my invention is to reproduce such a record in an improved manner whereby it is possible to reach the soft 20 tones and at the same time possible to reproduce the loud tones without blasting. These and other objects of my improvement will, however, hereinafter more fully appear.

In order that my invention may be clearly 25 and fully disclosed, I have shown for purposes of illustration in the accompanying drawings one embodiment which the same may assume in practice.

In these drawings,—

30 Figure 1 is a partial central sectional view of the box, the needle arm being shown partially in elevation.

Fig. 2 is an enlarged detail sectional view 35 showing the disk supporting and clamping means, the view being taken on the same line as Fig. 1.

In this illustrative construction, it will be noted that I have shown a sound box 1, formed of any suitable material and preferably of bronze, having an open front and an axial sound opening 2 in its rear wall adapted to coincide with a suitable registering opening 3 in a sound arm or in a sleeve 4, attached to the member 1 by suitable 40 means, as screws 5, and itself adapted to be suitably removably attached to a sound arm, or if desired to be formed integral with such an element. As shown, it will also be noted that this box 1 is provided with a flanged 45 portion 6 on its periphery, and that within this flanged portion is disposed the reproducing mechanism, the same being clamped in operative position within the flange by suitable means, herein shown to include, for 50 instance, a removable ring 7, preferably threaded at 8 to the inner periphery of the flange.

The reproducing mechanism carried within the box 1 is shown herein to comprise a plurality of flexible disks 9 and 10 herein of substantially equal thickness, which while they may be made of equivalent material, are preferably formed of relatively thick mica, as I find that, in my improved construction, this material is well adapted to accurate reproduction over a wide range of sound. As shown, these two disks 9 and 10 are of slightly less diameter than the inner diameter of the box and are disposed therein parallel to each other and with their outer 60 surfaces adjacent their peripheries engageable with suitable washers 11 which are formed of a material adapted to permit the disks to slide readily during abnormal vibrations, and yet during normal vibrations 65 hold the disks within the desired clamped relation established by the ring 7. While other materials having an equivalent function may be used in making these washers, I preferably form the same of chamois, as 70 I find that this material permits the disks to slide readily and that it also possesses excellent wearing qualities. In a preferred form 75 of my invention, I also coat or load the surface of these chamois washers with some friction reducing substance, as for instance talc or an equivalent, in such a manner as thereby further to enhance the facility of movement of the disks by further reducing the friction. As shown, not only are the 80 washers 11 disposed on opposite sides of the members 9 and 10, but another washer 11 of the same material, and preferably similarly treated, is preferably disposed between 85 the inner surfaces adjacent the peripheries 90 of the disks. As illustrated, suitable yielding mountings, as for instance rubber rings 12, are preferably also disposed on the opposite sides of the outside washers 11, one 95 of the same preferably being seated in a 100 suitable annular groove 13 provided near the base of the inner periphery of the flange 6, while the other is adapted to engage the clamping means and be compressed thereby 105 to compress the other elements into the desired operative relation described above. In a preferred form of my invention I also provide a suitable means between the outer

rubber ring 12 and the ring 7 in order to overcome the objectionable disarrangement following from the rotation of the rubber ring and possibly of other inner elements as 5 the ring 7 is screwed into its operative position. As shown, these means assume the form of a ring 14 which is preferably formed of metal and provided with a projection or tongue 15 on its outer periphery adapted to 10 enter a corresponding groove 16 in the threaded inner periphery of the flange 6.

Operatively associated with each of these disks 9 and 10, is the means for transmitting to the same the vibration of the element 15 which engages the record. These means may obviously assume various forms. They are, however, herein shown as of the needle type including an exterior radially extending preferably rigid needle arm 18 vibrating 20 ably supported, as on a suitable freely moving pivot 19, on a suitable support 20, preferably attached to the box 1. As shown, the outer end of the needle carrying arm is provided with a record traversing needle 21 of 25 usual form removably attached thereto by any suitable means, as by a setscrew 22. It will be noted, moreover, that the inner end of this arm 18 is provided with an inwardly extending portion 23 disposed substantially 30 at right angles thereto and to the disks, and preferably of reduced cross section and resiliently connected to the body portion of the member 18 as by an elbow 24, preferably formed by further reducing the material at 35 the elbow. It will also be noted that this portion 23 is provided with a suitably formed foot piece 25 disposed substantially coaxially with the disks and preferably flattened and smooth on its under surface so 40 that it may lie flat upon the outer surface of the outer disk 10 and be rigidly attached thereto and preferably also rigidly attached to the inner disk so that the disks are under equal stress. As shown, it will be noted 45 that a suitable attaching member, as for instance a screw 26, is provided, which is threaded into a suitable axially disposed opening formed in this foot 25, a suitable washer 27 preferably formed of metal or 50 other equivalent material being disposed between the head of the screw and the outside surface of the disk 9 to protect the latter, while the body of the screw extends through suitable axial perforations in the disks 9 and 55 10 to the foot 25. As shown, a suitable washer 28 is disposed around the screw and between the disks 9 and 10, this washer preferably being formed of the same material as the washers 11 and treated in the same 60 manner.

As a result of my improved construction, it will be noted that, when the needle arm 18 is moved through its engagement with a record, the disks 9 and 10 will be vibrated 65 through the resilient connection 24, 23, the

two parallel disks being under equal stress and moving together. During the reproducing process it will also be observed that while the outer disk 9 vibrates in the same manner as the inner disk, it also acts as a deflector 70 throwing the sound back to the inner disk in such a manner as to increase the volume of the reproduction to substantially the volume of the original sound. It will also be noted that due to my improved construction 75 utilizing a plurality of operatively connected and slidably mounted diaphragms, the range of accurate reproduction of the device is materially increased, the same being adapted to reproduce even the third register without flatting, at the same time that it is made possible to reproduce those delicate modulations giving the so-called naturalness to a tone. By the use of my improved construction, it is also possible not only thus to increase materially the range and accuracy of 80 reproduction, but to reproduce very loud sounds without blasting, the blasting being effectively overcome through the use of my improved mounting for the disks whereby 85 when the same are expanded beyond their normal range, as, for example, by a heavy bass note, the same are enabled to move freely in their supports and without the introduction of foreign sounds resulting from 90 friction.

In my improved construction, it has been observed that it is possible to use even relatively thin and highly flexible disks of mica without encountering the difficulties in the 100 way of blasting heretofore encountered with reproducers utilizing a single thin disk. It has also been observed that, at the same time that blasting is overcome, I am able to overcome the difficulties in reaching low or soft 105 tones heretofore experienced with those reproducers wherein a relatively thick disk has been used in an effort to avoid the blasting encountered with a thin disk. In fact, in my improved construction wherein the disks 110 are under equal stress and slidably mounted, it has been demonstrated that even when the same is applied to the most difficult "test" records, the sound is reproduced both in far greater volume and with far more natural 115 quality than is obtainable with any known reproducer of the single or double disk type. It has further been demonstrated that this is true regardless of the volume or range of the original sound, my improved reproducing mechanism particularly being far more effective in bringing out either soft tones clearly or loud tones without blasting. In the use of my improved construction, it has also been found that it is adapted at will to 120 use upon machines of either the hill and dale or lateral type, it only being necessary to adjust the sound box into the desired angle relative to the record. Attention is here also directed to the fact that as a result of my 125 130

improved and simplified construction, the device may be very readily and cheaply manufactured and that it is entirely unnecessary to provide a cover for the sound box.

5 These and other advantages of my improvement will, however, be clearly apparent to those skilled in the art.

While I have in this application specifically described one embodiment which my 10 invention may assume in practice, it is to be understood that the same is shown herein for purposes of illustration and that the invention may be modified and embodied in various other forms without departing from 15 its spirit, it being my intention to include all such modifications within the scope of the appended claims.

What I claim as new and desire to secure by Letters Patent is:

20 1. In a sound reproducing mechanism, a sound box, a plurality of operatively connected reproducing elements therein disposed parallel to one another, and means whereby said elements may coöperate freely 25 in either direction.

2. In a sound reproducing mechanism, a sound box, a plurality of operatively connected reproducing elements therein disposed parallel to one another, and means 30 whereby said elements may move freely in unison in response to soft or loud tones.

3. In a sound reproducing mechanism, a sound box, a plurality of spaced parallel reproducing elements having their edges 35 clamped to permit a sliding movement therein, and vibrating means operatively connected to each of said elements.

4. In a sound reproducing mechanism, a sound box, a plurality of spaced parallel 40 reproducing elements having their edges clamped to permit a sliding movement therein, and resilient vibrating means operatively connected to each of said elements.

5. In a sound reproducing mechanism, a sound box, a plurality of spaced reproducing elements disposed in parallel planes and having their edges clamped to permit a sliding 45 movement therein, and resilient vibrating means operatively connected to each of said elements.

6. In a sound reproducing mechanism, a sound box, a plurality of spaced parallel reproducing elements, vibrating means operatively connected to each of the same, and 55 means normally clamping the edges of said elements adapted to permit a free sliding movement of said elements during abnormal vibrations thereof.

7. In a sound reproducing mechanism, a sound box, a plurality of spaced reproducing elements disposed in parallel planes, vibrating means rigidly connected to each of the same, and friction reducing means normally clamping the edges of said elements 65 adapted to permit a free sliding movement

of said elements during abnormal vibrations thereof.

8. In a sound reproducing mechanism, a sound box, a plurality of spaced parallel reproducing disks, resilient vibrating means 70 rigidly connected to each of the same, and means normally clamping the surfaces adjacent the peripheries of said disks adapted to permit a free sliding movement of said disks during abnormal vibrations thereof. 75

9. In a sound reproducing mechanism, a sound box, a plurality of spaced reproducing disks disposed in parallel relation therein, peripheral clamping means therefor including friction reducing surfaces engageable 80 slidably by certain of the surfaces adjacent the peripheries of said disks, and vibrating means for said disks operatively connected to each of the same at the axis thereof.

10. In a sound reproducing mechanism, a sound box, a plurality of spaced reproducing disks disposed in parallel relation therein, peripheral clamping means therefor including friction reducing surfaces engageable 85 slidably by the inner surfaces adjacent the peripheries of each of said disks, and vibrating means for said disks operatively connected to each of the same at the axis thereof. 90

11. In a sound reproducing mechanism, a sound box, a plurality of spaced reproducing disks disposed in parallel relation therein, peripheral clamping means therefor including friction reducing surfaces engageable 95 slidably by surfaces adjacent the peripheries of each of said disks, and vibrating means for said disks operatively connected to each of the same at the axis thereof. 100

12. In a sound reproducing mechanism, a sound box, a plurality of spaced parallel 105 disks therein, peripheral clamping means therefor including surfaces loaded with a friction reducing agent and engageable slidably by the inner and outer peripheries of said disks, and resilient means for transmitting vibration to said disks rigidly connected to each of the same at the axis thereof. 110

13. In a sound reproducing mechanism, a sound box, a plurality of spaced parallel disks therein, peripheral clamping means 115 therefor including washers loaded with a friction reducing agent and engageable slidably by the inner and outer surfaces adjacent the peripheries of said disks and yielding washers engaging said outside washers, 120 and means for transmitting vibration to said disks operatively connected to each of the same at the axis thereof.

14. In a sound reproducing mechanism, a sound box, a plurality of spaced parallel 125 disks therein, peripheral clamping means therefor including washers loaded with a friction reducing agent and engageable slidably by the inner and outer surfaces adjacent the peripheries of said disks, and 130

- means for transmitting vibration to said disks connected to each of the same at the axis thereof and including an axially disposed washer located between said disks.
- 5 15. In a sound reproducing mechanism, a sound box, a plurality of spaced substantially parallel disks therein, peripheral clamping means therefor including friction reducing washers engageable slidably by the inner and outer surfaces adjacent the peripheries of said disks, and means for transmitting vibration to said disks rigidly connected to each of the same at the axis thereof and including an axially disposed friction reducing washer located between said disks.
- 10 16. In a sound reproducing mechanism, a sound box, a plurality of spaced parallel disks therein, friction reducing washers engageable slidably by the inner and outer surfaces adjacent the peripheries of said disks, means for clamping said washers and the edges of said disks to said box, a needle arm pivotally supported on said box having a resiliently connected portion disposed substantially coaxially with said disks, and
- 15 20 25

means for rigidly attaching said portion to the axis of each of said disks including an axially disposed friction reducing washer between said disks.

17. In a sound reproducing mechanism, a sound box, a plurality of spaced parallel mica disks therein, chamois washers loaded with a friction reducing agent and engageable slidably by the inner and outer surfaces adjacent the peripheries of said disks, yielding washers engaging said outside washers, a non-rotating ring interlocked with said box and engaging one of said yielding washers, a ring threaded into said box and engaging said ring, a needle arm pivotally supported on said box having a resiliently connected portion disposed substantially coaxially with said disks, and means for attaching said portion to the axis of each of said disks including a similar axially disposed friction reducing washer between said disks.

In testimony whereof I affix my signature.

CHAS. H. ALLEN.
